ATTORNEY.

UNITED STATES PATENT OFFICE.

JOHN G. YANCHIK, OF WILKES-BARRE, PENNSYLVANIA.

LOCK.

Application filed October 11, 1920. Serial No. 416,005.

To all whom it may concern:

Be it known that I, JOHN G. YANCHIK, a citizen of the United States, residing at Wilkes-Barre, in the county of Luzerne and

5 State of Pennsylvania, have invented certain new and useful Improvements in Locks, of which the following is a specification.

This invention relates to new and useful improvements in closure devices, and more 10 particularly to devices adapted to lock a plurality of drawers or doors.

The primary object of the invention is to provide a locking mechanism of the above nature in which it is unnecessary to operate 15 a master drawer to cause other drawers to become locked, whereby certain of the drawers may be locked while others may remain open.

Another object of the invention is to provide a device of the above nature wherein 20 the latch mechanism automatically returns to a locked position immediately after the locking mechanism has been actuated to release the drawers, thereby making it possible to lock the drawers independently of 25 each other.

A further object of the invention is to provide means for causing the drawers to spring to an open position as soon as the lock mechanism has been actuated to release 30 the drawers, whereby the keepers therefor may become disengaged from the locking mechanism which automatically returns to a locked position when the locking mechanism has been actuated to release the drawers.

35 Still another object of the invention is to provide a device of the above nature having key-actuated means for controlling the locking mechanism.

40 Other objects and advantages of the invention will become apparent during the course of the following description.

In the accompanying drawings forming a part of the application and wherein like numerals are employed to designate like parts 45 throughout the several views—

Figure 1 is a prospective view of a piece of furniture having the invention applied thereto.

Figure 2 is a horizontal section there- 50 through illustrating the invention applied thereto.

Figure 3 is an enlarged section of the lock.

Figure 4 is a detailed view of one of the keepers employed in the invention.

55 Figure 5 is a transverse section of the

same taken on the line 5—5 of Figure 4, and

Figure 6 is an enlarged fragmentary section taken on the line 6—6 of Figure 2.

In the accompanying drawings wherein for the purpose of illustration is shown the 60 preferred embodiment of the invention, the numeral 7 indicates a piece of furniture, such as a desk having a plurality of vertically aligned drawers slidably mounted therein, and a hinged closure or door 9. The 65 drawers are slidably mounted in the usual manner upon guides 10 more clearly seen in Figure 2, which are supported at their innermost ends by a skeleton supporting structure 11. This structure includes horizontal 70 bars 12 arranged in back of each drawer and a pair of projectors 13 are associated with each bar 12. These projectors each include a casing having a spring pressed plunger 14 associated therewith in a manner that the 75 plunger normally bears against the back of the drawer so that when the latter is released by the locking mechanism the drawer slides to an open position.

The back of each drawer is provided with 80 a rearwardly projecting keeper 15 as most clearly seen in Figs. 2 and 4 and consists of a rearwardly or inwardly projecting body portion to the free end of which is hinged as at 17 a nose 18. A spring 19 is inter- 85 posed between the nose and body portion and is fastened to the former whereby the nose is arranged laterally of the body portion. This nose is equipped at its free end with an integral arm 20 which extends to- 90 ward the body portion, the inner end of which is provided with an angular extension 21. This angular extension is adapted for engagement with the arch portion of a U- 95 shaped retaining member 22, the free ends of which are pivotally connected to opposite sides of the body portion as clearly seen. Consequently the retaining member limits the outward swinging movement of the nose, but still permits of the same moving in- 100 wardly toward the body portion. A similar keeper 15 is secured to the inner surface of the door 9.

The locking mechanism consists of a latch member 23 for each drawer. Each latch 105 member has its free end provided with a hook or nose adapted for engagement with the movable nose of its respective keeper, and the opposite end of the latch member is secured in any desired manner to a shaft 24. 110

This shaft is vertically arranged in back of the drawers 8 and is of a sufficient length to insure connection of all of the latch members thereto. The shaft is mounted for oscillation and to the side opposite said latch member is secured a laterally projecting connector element which is pivotally connected at its free end to one end of a rod 26. The opposite end of this rod is pivotally connected to a similar connector element 27 which is secured to a second vertically arranged shaft 28, which may be termed an oscillatory member.

An arm 29 is secured to the oscillatory member 28 to project laterally therefrom and at substantially right angles to the connector element 27 so that its free end may be pivotally associated adjacent one end with an actuator rod 30. The end of the actuator rod adjacent the slot is extended into a casing 31 so that a coiled spring 32 arranged therein to encircle the free end of the actuator rod may engage with a pin 33 secured transversely of the free end of the rod and with the end of the casing so that the actuator rod is normally retained in a position to cause the latch members 23 to be normally arranged in locked positions. The opposite end of the actuator rod is connected to the end of a trip lever 34 which is pivotally mounted between its ends in an opening provided in the side of the desk. The free end of the trip lever projects beyond the side of the desk to be disposed within a lock casing 35, the face of which is provided with an elongated slot 36 having an enlarged opening between its ends for the admission of a key 37. Secured to the inner surfaces of opposite sides of the lock casing 35 and at the ends of the key slot 36, a pair of spaced inwardly projecting lugs 38 are secured. It is to be noted that the pairs of lugs at opposite ends of the slots are arranged upon opposite sides of the slots as clearly shown in Figure 3, so that the proper key 37 having its end provided with oppositely extending projections 39 may be turned to permit the fingers 39 of the key passing between the spaced lugs 38 and engaging with the free end of the trip lever 34 in order to move the actuator rod 30.

The locking mechanism also includes means for locking the door 9, and includes an angle lever 40 pivoted at the angle thereof to a depending post 41 secured to the under side to the top of the desk top. One arm of the angle lever is pivotally associated with a slot in the end of the actuator rod adjacent the connection with the trip lever, while the free end of the other arm of the angle lever is pivotally connected to a link 42. The opposite end of this link is pivotally connected to a latch lever 43 which is pivoted between its ends and provided with a nose for engagement with the keeper

15 secured to the door. It will of course be obvious that a projector 13 may also be associated with the door whereby the same is swung open when the lock mechanism is actuated to release the same. In the operation of the device and assuming that all drawers and the door 9 are in a closed position as shown in Figure 2, and it is desired to unlock the drawers, the key 37 is inserted into the casing and turned so that one of the projecting fingers 39 will lift the free end of the trip 34. This action will cause the actuator rod 30 to be pulled toward the front of the desk and against tension of the coiled spring 32 in the casing 31. Movement of the actuator rod will actuate the member 28 and through the intermediacy of connecting elements heretofore set forth will turn the shaft 24 in a direction to cause the latch members to disengage the keepers 15. The projectors 13 will immediately cause the drawers and door to swing open so that the automatically returning latch members will not engage the keeper again to lock the drawers. As stated before, the latch members are returned to their locked position in the path of movement of the keepers by the coiled spring 32 in the casing 31 acting upon the actuator rod 30.

It will also be obvious that while the actuator rod 30 is being moved toward the front of the desk, the angle lever 40 will pivot and cause the latch member 43 of the door through the intermediacy of the link 42 to pivot and disengage the nose of the keeper for the door. The latch members 23 and 43 being automatically returned to their locked positions as soon as the locking mechanism is actuated, it will be obvious that any of the drawers or the door may be closed and locked independently of the others and of the master drawer such as known in the prior art. When a drawer is closed, it will be seen that the nose 18 of the keeper therefore will be impinged by the nose of its respective latch member whereby it will be moved toward the body portion of the keeper so that it may move clear of the latch nose, then spring behind the same to retain the drawer in a locked position.

The foregoing description and the accompanying drawings have reference to the preferred or approved embodiment of my invention. It is to be understood however, that such changes may be made in construction and arrangement of parts, materials, dimensions, etc., as may prove expedient and fall within the scope of the appended claims.

Having thus fully described my invention what I claim as new and desire to secure by Letters Patent is:—

1. In a drawer and door lock, a keeper comprising an attaching and supporting body, a nose pivotally secured to the outer

end of the body, spring means normally retaining the nose spaced from the body, an inwardly extending arm formed on the free end of the nose and extending toward the body, an angular extension formed on the arm, and a U-shaped guide and retaining member carried by the body for receiving the angular extension.

2. In a drawer and door lock, a movable member, a rock shaft disposed in rear of the movable member, a keeper including a body secured to the rear end of the movable

member, a pivoted spring pressed nose carried by the body, a latch carried by the rock shaft, and means for operating the shaft for normally holding the latch in the path of the pivoted nose. 15

In testimony whereof I affix my signature in presence of two witnesses.

JOHN G. YANCHIK.
